UNITED STATES PATENT OFFICE.

JOSEPH P. DELAHUNTY, OF WEST PITTSSTON, PENNSYLVANIA.

DYEING-MACHINE.

SPECIFICATION forming part of Letters Patent No. 416,854, dated February 24, 1891.

Application filed April 15, 1890. Serial No. 347,983. (No model.)

To all whom it may concern:

Be it known that I, JOSEPH P. DELAHUNTY, of West Pittston, Luzerne county, and State of Pennsylvania, have invented an Improvement in Dyeing-Machines, of which the following is a specification.

My invention relates to dyeing-machines; and it consists of certain improvements which are fully set forth in the following specification and shown in the accompanying drawings, which form a part thereof.

The object of my invention is to construct a dyeing-machine for dyeing skeins of yarn, wherein the yarn may be supported upon rollers arranged above the liquid in the tank, and may be alternately lowered into the liquid and raised therefrom, the time in which the yarn is in the liquid being preferably a great deal longer than the time in which it is lifted clear of the liquid, or substantially clear of the same, and exposed to the action of the atmosphere. Furthermore, when the yarn is raised clear of the liquid the rollers which support it are caused to rotate, whereby the skeins may be rotated so as to insure every portion of the yarn being treated alike.

In the construction employed by me the yarn is hung on a series of parallel rollers, which are so constructed as to keep the several skeins apart, and the adjacent portions of two skeins of yarn on different rollers are caused to travel in the same direction, so as to avoid any possibility of tangling.

Referring to the drawings, Figure 1 is a side elevation of a dyeing-machine embodying my invention, with the lower portion of the machine made in section. Fig. 2 is an end elevation of my improved dyeing-machine, with the dye-vat made in section. Fig. 3 is a side elevation of automatic mechanism whereby the yarn may be supported within the liquor a great deal longer than the time it is supported out of the liquor, and Fig. 4 is a perspective view of the cam shown in Fig. 3.

A is a dye-tank, and may be made of metal or wood in any suitable manner. As shown, it is rectangular, and is provided with a superstructure or frame-work B. At each end of the dye-vat and guided in the frame-work B is a carriage C, in which are journaled a series of rollers D, which extend the length of the vat A and are formed with grooves, as shown in Fig. 1, whereby the various skeins of yarn hung thereon will remain separated.

These rollers D are removably connected with the carriages C, or one end at least is so removable as to permit the placing of the yarn upon said roller. The various rollers D are connected together at one end by spur-gearing d, so that the adjacent rollers rotate in opposite directions for the purpose of insuring the adjacent yarn traveling in the same direction.

Arranged at the upper part of the machine is a shaft F, carrying at each end a crank f, to which are hinged the links K, connecting at the lower part with the carriages C. By rotating the shaft it is seen that the carriages and the rollers D will be raised and lowered with respect to the vat for the purpose of dipping and removing the skeins supported upon the rollers. This shaft F may be rotated by means of a pinion H, which gears with a spur-wheel G upon the shaft F. The pinion H is secured upon a shaft I, which may be driven by a belt-pulley J, or otherwise, as desired.

Secured to the shaft F is a sprocket-wheel M', about which passes a sprocket-chain m', the other end of which rotates a similar sprocket-wheel N', secured to a shaft upon which another sprocket-wheel M is secured. Pivoted to the axis of the sprocket-wheel M is an arm L, carrying at its other end a sprocket-wheel M², similar to the one last described, and about these two sprocket-wheels passes an endless sprocket-chain m. The free end of the arm L may be guided in the curved guideway l, if desired, permitting a given amount of vertical movement to the sprocket-chain. This sprocket-chain m, it will be seen, is constantly traveling, and when the carriages C are raised a sprocket-wheel E on the end of one of the rollers D is brought into contact with the traveling sprocket-chain, and thereby imparts a rotary movement to the several rollers D. The loose connection of the arm L prevents binding, and also enables the sprocket-chain to be maintained in connection with the sprocket-wheel E during a longer period. The cranks f may be adjustable, if desired, to vary the reciprocation of the carriage.

I will now refer to the mechanism which may be employed for supporting the skeins of yarn a longer time in the liquid than that occupied while they are raised clear of the liquid.

Referring to Fig. 3, the pinion H is secured

to the shaft I as before, and upon said shaft is a clutch S, adapted for connection with a belt-wheel J. Secured to the belt-wheel is a worm N, which meshes with a worm-wheel O, which latter wheel, through the gearing P, rotates a cam Q, having the cut-away portion q. (Best shown in Fig. 4.)

R is a lever for operating the clutch S, and is pulled against the cam Q by a spring r. 10 When in the position shown in Fig. 3, the rollers D are in their lowest position. As the wheel J rotates the cam Q is gradually rotated until the cut-away portion q permits the lever R to be drawn to the left of the spring r, forcing the clutch S into contact with the wheel J. A further motion of the wheel J then rotates the shaft I, and through the gearing II G rotates the crank f and lifts the carriages and their rollers into their upper positions. 20

The length of the notched part q with reference to the other portions governs the relative time that the carriages and the rollers are held in an elevated position with respect 25 to the time occupied in their lowest position. The proportion of the gearing should be such that as soon as the cranks f are in their lowest position the clutch should be thrown out of action, so that for one revolution of the 30 shaft F the cam Q should make a portion of a revolution equal to the length of the cut-away portion q.

The carriages and their rollers may be counterbalanced by means of weights C', connected 35. to cords c, passing from the carriages over suitable pulleys arranged above the free ends of the rollers and each connected with said weights C'.

I do not limit myself to any particular 40 mechanism for accomplishing this result as to the time of elevation and depression of the carriages and rollers, as it may be modified in various ways and still accomplish the same result. The various details of the machine 45 may be modified without in the least departing from the spirit of the invention.

Having now described my invention, what I claim as new, and desire to secure by Letters Patent, is—

50 1. In a dyeing-machine, the combination of a dye-vat, a reciprocating yarn-supporting roller, intermittently-operating mechanism for raising and lowering said roller, and means whereby the operation of said mechanism for raising and lowering the rollers is interrupted after each raising and lowering operation.

2. In a dyeing-machine, the combination of a dye-vat, a reciprocating yarn-supporting roller, intermittently-operating mechanism 60 for raising and lowering said roller, means whereby the operation of said mechanism for raising and lowering the rollers is interrupted after each raising and lowering operation, and mechanical devices to rotate said roller when in its raised position.

3. In a dyeing-machine, the combination,

70 with a dye-vat, of one or more yarn-supporting rollers arranged above the vat and movable to and from the liquid therein, mechanical devices to raise and lower said rollers, a power-shaft, a clutch to connect and disconnect said power-shaft, the devices for raising and lowering the rollers, and a cam for operating the clutch.

4. The combination of a dye-vat, a roller 75 movable to and from the liquid in the vat, upon which the skeins of yarn are placed, a traveling sprocket-chain, and a sprocket-wheel on the roller adapted to be brought in connection with the sprocket-chain when said roller is 80 moved away from the liquid in the dye-vat.

5. The combination of a dye-vat, a roller 85 movable to and from the liquor in the dye-vat, a moving sprocket-chain supported with provision for vertical displacement, and a 90 sprocket-wheel carried upon the roller and adapted to come into contact with the sprocket-chain when the roller is raised or moved away from the liquid in the dye-vat.

6. The combination of a dye-vat, a vertically-movable carriage at each end of the vat, two or more rollers supported by said carriages, gearing between the said rollers, so as to rotate with adjacent rollers in opposite directions, power mechanism for raising and 95 lowering the carriages and their rollers, and means, substantially as set out, to rotate the rollers when in their raised position.

7. In a dyeing-machine, the combination, 100 with a dye-vat, of one or more yarn-supporting rollers arranged above the vat and movable to and from the liquid therein, mechanical devices to raise and lower said rollers, a power-shaft, a clutch to connect and disconnect said power-shaft, the devices for raising 105 and lowering the rollers, a cam for operating the clutch, and power-transmitting connections between the power-shaft and cam.

8. In a dyeing-machine, the combination of a dye-vat, carriages for supporting a series 110 of rollers above the vat, rollers supported by said carriages, a power-shaft arranged above the vat, cranks carried by said shaft, links connecting the cranks and carriages, and guides for the carriages while they are being 115 raised and lowered.

9. The combination of a dye-vat, carriages 120 for supporting rollers, a series of yarn-supporting rollers arranged parallel with respect to each other, gearing between the several 125 rollers to cause them to rotate simultaneously, the adjacent rollers rotating in opposite directions, power mechanism for raising and lowering said rollers, and means for rotating said rollers when in their raised positions.

In testimony of which invention I have hereunto set my hand,

JOSEPH B. DEHAN F. N.Y.
